H. A. THOMPSON

RAILWAY TRAFFIC CONTROLLING APPARATUS

Original Filed Feb. 5, 1926

UNITED STATES PATENT OFFICE.

HOWARD A. THOMPSON, OF EDGEWOOD BOROUGH, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY-TRAFFIC-CONTROLLING APPARATUS.

Application filed February 5, 1926, Serial No. 86,306. Renewed April 25, 1928.

My invention relates to railway traffic controlling apparatus, and particularly to apparatus of the type comprising traffic governing means controlled by current flowing in 5 the track rails.

I will describe one form of railway traffic controlling apparatus embodying my invention, and will then point out the novel features thereof in claims.

10 The accompanying drawing is a diagrammatic view illustrating one form of railway traffic controlling apparatus embodying my invention.

Referring to this drawing, the reference 15 characters 1 and 1^a designate the track rails of a stretch of railway track over which traffic normally moves in the direction indicated by the arrow. These track rails are divided, by means of insulated joints 2, into a plurality of successive track sections A—B, B—C, etc. Each track section is provided 20 with a track transformer designated by the reference character T with a suitable distinguishing exponent and having a secondary 25 connected across the rails adjacent the exit end of the associated section in series with a reactor 6. The primary 26 of each track transformer T is constantly supplied 30 with alternating current from secondary 27 of an associated line transformer designated by the reference character L with an exponent corresponding to the location. The primary 28 of each line transformer L is constantly supplied with alternating current 35 from a suitable source such as an alternator Q over line wires 3 and 3^a.

Each track section is also provided with two track relays designated by the reference characters D and E, respectively, with exponents 40 corresponding to the location and connected in parallel across the rails of the associated section adjacent the entrance end thereof. An asymmetrical unit 4 is interposed between each relay D and the rails of 45 the associated section, and a similar asymmetrical unit 5 is interposed between each relay E and the rails of the corresponding section. The asymmetrical units 4 and 5 are oppositely disposed so as to permit current 50 of one polarity but not of the other to flow through one track relay and to permit current of the other polarity but not of the first polarity to flow through the other track relay. That is to say, during one-half of each

cycle of the alternating current supplied to 55 the rails of a section, by the transformer T associated therewith, current flows through relay D for that section and not through the associated relay E. During the other half of each cycle current flows through relay E and 60 not through relay D.

The asymmetrical units 4 and 5 may be of any suitable type, such for example, as the units disclosed and claimed in an application 65 for Letters Patent of the United States, Serial No. 1111, filed January 7, 1925, by Lars O. Grondahl, for uni-directional current carrying devices.

It will be clear from the foregoing that 70 each track section is provided with a track circuit comprising the secondary 25 of a track transformer T, a reactor 6, the rails 1 and 1^a of the section in series, and two track relays D and E with their associated asymmetrical units connected in parallel. When the track 75 section is unoccupied, the alternating current supplied thereto by the track transformer energizes both the track relays D and E. When the section is occupied, however, current is shunted away from the track relays 80 by the wheels and axles of the train and relays D and E are both deenergized.

One advantage of track circuits embodying 85 my invention is that stray direct currents in the track rails cannot energize both the track relays. Any stray direct current in the rails of a track section can flow through only one of the track relays connected with that section, and is prevented from flowing through the other relay by the asymmetrical 90 unit associated with such relay. It will be plain therefore that the track relays D and E will both be energized only when alternating current is being supplied to the rails of the section.

The track circuits which I have described 95 may be used to control traffic governing means of any suitable type. As here shown a track-way signal is located adjacent the entrance end of each track section. Each of the signals is designated by the reference character S with an exponent corresponding to the location and in the form here shown comprises a semaphore signal capable of indicating "proceed", "caution" or "stop".

100 Each track section is provided also with a line relay designated by the reference character K with an appropriate distinguishing

exponent. Referring particularly to relay K^A , this relay is energized only when the track relays for sections A—B and B—C are all energized, the circuit for this relay passing from secondary 27 of line transformer L^A , through wires 29 and 30, front contact 31 of relay E^A , wire 32, front contact 33 of relay D^B , wire 34, front contact 35 of relay E^A , wire 36, front contact 37 of relay D^A , wire 38, winding of relay K^A and wires 39, 21, 40 and 41 back to secondary 27 of transformer L^B . The circuit for each of the remaining line relays K is similar to that just traced for line relay K^A .

Each signal S is controlled by the track relays and by the line relay associated therewith. Referring particularly to signal S^A , this signal is provided with a caution circuit which may be traced from secondary 27 of transformer L^A , through wires 7 and 8, front contact 9 of relay D^A , wire 10, front contact 11 of relay E^A , wires 12 and 13, operating mechanism of signal S^A , wires 14, 15 and 16, front contact 17 of relay E^A , wire 18, front contact 19 of relay D^A , and wires 20, 21 and 21^a, back to secondary 27 of transformer L^A . This circuit is closed only when track relays D^A and E^A are energized, under which conditions, if relay K^A is open, signal S^A displays a caution indication. (See signal S^B). If line relay K^A is also energized, current flows from secondary 27 of transformer L^A , through wires 7 and 8, front contact 9 of relay D^A , wire 10, front contact 11 of relay E^A , wires 12 and 22, front contact 23 of relay K^A , wire 24, operating mechanism of signal S^A , wires 14, 15 and 16, front contact 17 of relay E^A , wire 18, front contact 19 of relay D^A , and wires 20, 21 and 21^a back to secondary 27 of transformer L^A . When this circuit is closed, signal S^A displays a proceed indication. It will be seen that when either relay D^A or E^A is de-energized, both the caution and proceed circuits just traced are open so that the signals S^A indicates stop, and furthermore, the closing of back contact 9 of relay D^A or of back contact 11 of relay E^A will short circuit the operating mechanism of signal S^A .

In the stretch illustrated in the drawing, the section immediately to the right of point C is occupied by a train indicated diagrammatically at V. Current is therefore shunted away from relays D^C and E^C and these relays are de-energized. Relay K^C is therefore also de-energized, and signal S^C indicates stop. Current is supplied to section B—C by transformer T^C and relays D^B and E^B are both energized. Relay K^B is de-energized however, its circuit being open at front contacts 33 and 31 of relays D^C and E^C , respectively. The caution circuit for signal S^B is therefore closed but the proceed circuit for this signal is open at front contact 23 of relay K^B . Signal S^B therefore displays a caution indi-

cation. The alternating current supplied to section A—B by transformer T^B energizes relays D^A and E^A . Relay K^A is also energized over front contacts of relays D^A , E^A , D^B and E^B and the proceed circuit for signal S^A is therefore closed so that this signal displays a proceed indication.

It should be pointed out that stray direct current in section A—B or B—C can have no effect upon the apparatus because the track relays for these sections are already energized by alternating current supplied thereto by the track transformers. Furthermore, stray direct current in the section to the right of point C can pick up only one of the track relays D^C or E^C , depending upon the polarity of such stray current, and this cannot cause signal S^C to indicate caution or proceed. In other words, the apparatus herein described is absolutely immune to the effect of stray direct current in the trackway, because such direct current cannot cause a less restrictive condition of the traffic governing means controlled by the track circuits.

Although I have herein shown and described only one form of railway traffic controlling apparatus embodying my invention, it is understood that various changes and modifications may be made therein within the scope of the appended claims without departing from the spirit and scope of my invention.

Having thus described my invention, what I claim is:

1. In combination, a section of railway track, a source of alternating current constantly connected with the rails of said section, two relays connected with the rails of said section, asymmetrical units associated with said relays for permitting current of one polarity but not of the other to pass through one relay and for permitting current of the other polarity but not of the first polarity to pass through the other relay, and traffic governing means controlled by said relays.

2. In combination, a section of railway track, a source of alternating current connected with the rails of said section, two relays connected with the rails of said section, asymmetrical units associated with said relays for permitting current of one polarity but not of the other to pass through one relay and for permitting current of the other polarity but not of the first polarity to pass through the other relay, a third relay controlled by said two relays, and by traffic conditions in advance of said section, and traffic governing means controlled by all three relays.

3. In combination, a plurality of successive sections of railway track, means for supplying alternating current to the rails of each such section, two track relays connected with the rails of each such section, asymmetrical units associated with the track relays for each

section for permitting current of one polarity to pass through one track relay and for permitting current of the other polarity but not the first to pass through the other relay, a 5 line relay for each section controlled by the two track relays for the associated section and by traffic conditions in advance of said section, and traffic governing means for each section controlled by the associated track relays 10 and line relay.

4. In combination, a plurality of successive sections of railway track, means for supplying alternating current to the rails of each such section, two track relays connected with 15 the rails of each such section, asymmetrical units associated with the track relays for each section for permitting current of one polarity to pass through one track relay and for permitting current of the other polarity but 20 not the first to pass through the other relay, a line relay for each section controlled by the track relays for the associated section and by the track relays for an adjacent section, and traffic governing means for each section controlled by the associated track relays and line 25 relay.

5. In combination, a plurality of successive sections of railway track, means for supplying alternating current to the rails of each such section, two track relays connected with 30 the rails of each such section, asymmetrical

units associated with the track relays for each section for permitting current of one polarity to pass through one track relay and for permitting current of the other polarity but 35 not the first to pass through the other relay, a line relay for each section, a circuit for each line relay including a front contact on each track relay for the associated section and a front contact on each track relay for an adjacent section, a trackway signal, a caution circuit for said signal including a front contact on each associated track relay, and a proceed circuit for each signal including a front contact on the associated line relay and a 40 front contact on each associated track relay. 45

6. In combination, a section of railway track, a source of alternating current constantly connected with the rails of said section, two relays connected with the rails of 50 said section, asymmetrical units associated with said relays for permitting current of one polarity but not of the other to pass through one relay and for permitting current of the other polarity but not of the first polarity to 55 pass through the other relay, a trackway signal for said section, a caution circuit for said signal including a front contact on each such relay, and means for shunting said signal when either said relay is de-energized. 60

In testimony whereof I affix my signature.
HOWARD A. THOMPSON.
